UNITED STATES PATENT OFFICE

JULIEN BERGÉ, OF TIRLEMONT, BELGIUM, ASSIGNOR TO RAFFINERIE TIRLEMONTOISE
SOCIÉTÉ ANONYME, OF TIRLEMONT, BELGIUM, A CORPORATION

PROCESS FOR DESUGARING SYRUPS AND MOLASSES

No Drawing. Original application filed February 6, 1928, Serial No. 252,417, and in Germany January 28, 1927. Divided and this application filed August 21, 1929. Serial No. 387,552.

The mother syrups or liquors obtained by centrifuging massecuites are again boiled to obtain a new massecuite and the process of centrifuging is repeated and the syrup thrown off from the new massecuite may be again boiled to produce a fresh massecuite. The same process may be continued successively until the syrup is practically desugared and leaves what is technically designated as molasses.

But this process of desugaring by constantly reboiling and centrifuging is in reality only practiced up to a certain point, as the mass, when too highly concentrated, is no longer sufficiently liquid to undergo a further boiling process and great difficulty would be experienced in discharging it from the vacuum pan.

After completion of the first boiling process, the mass has a crystal content of approximately 75%, so that 25% of the mother syrup still remains. This high percentage of mother syrup causes the formation of a thick coating around the crystals. In the subsequent treatment of the mass in the coolers or crystallizers, to attain a further desugaring, the thickness of said layer of syrup and the viscosity prevents an effective desugaring, so that this process is extremely ineffective.

The object of this invention comprises a method by which a more complete desugaring of the syrup is obtained by covering sugar crystals with a thin layer of the syrup. In a similar manner molasses can also be treated by this method, if its purity is to be further decreased.

The process is effected differently according to whether the syrup is still present in massecuite as mother syrup or is already separated. When the syrup is still in the massecuite, pure sugar crystals are admixed to the latter in a suitable manner, in order to increase the crystallization surface, owing to the increase in the number of crystals, and at the same time to reduce the thickness of the syrup layer surrounding the crystals. The pure sugar crystals may be added in such quantity that a sugar is finally produced from the massecuite, the crystals of which

are similar to raw sugar crystals, surrounded by 15% of syrup.

When the syrup is already separated, the process is carried out by spraying syrup on pure sugar crystals, or mixing it with them in the required proportion to obtain a sugar of the raw sugar type.

The process of the present invention may be carried out by different steps. When sugar is added to the massecuite in coolers, as large a quantity of pure crystals may be admixed, as the construction of the coolers allows, or coolers of special design may be employed, which by a suitable admixture of pure crystals will enable the massecuite to be thoroughly and effectively converted into raw sugar. In prior processes, the massecuite is centrifuged, so that syrup, as well as raw sugar, is obtained.

Another method of carrying out the process consists in depositing the syrup among pure sugar crystals whereby raw sugar is also obtained.

This process may likewise be applied in different ways; for instance, by admixing the syrups in excess with pure crystals in which case the excess syrup is thrown off by centrifugal action. In this manner an absolutely uniform coating of the crystals with sugar is assured and the syrup thrown off may then be admixed to a fresh quantity of crystals.

On cooling, evaporation, etc., the thin layer of syrup or molasses surrounding the crystals readily yields a portion of its sugar adhering by crystallization to the exhausting sugar, and this action may be still further increased by a suitable treatment of the sugar during storage by maintaining in the storeroom a proper degree of moisture and/or temperature, or by adopting other suitable measures in the storage room.

Finally, the adherent syrup is separated from the crystals by subjecting it to a particularly high centrifugal force as described in my Patent 1,775,385, September 9, 1930, issued on my co-pending application Serial No. 167,598, filed February 11, 1927. The crystals obtained in this manner may be used

2
as pure crystals for desugaring syrup or molasses according to the foregoing process.

This application is a division of applicant's co-pending application Serial No. 252, 5 417, filed February 6, 1928.

What I claim is:—

1. A method for crystallizing sugar from solutions, comprising admixing sugar crystals with massecuite to form a mass having 10 a relatively large quantity of sugar crystals comprising about 85% of the mass and a relatively small quantity of syrup comprising about 15% of the mass so that the syrup is widely distributed over the surfaces of the 15 sugar crystals and substantially all of the syrup is brought into close and intimate contact with the sugar crystals, and then cooling the mass.

2. A method for crystallizing sugar from 20 solutions, comprising admixing sugar crystals with massecuite to form a mass having a relatively large quantity of sugar crystals comprising about 85% of the mass and a relatively small quantity of syrup comprising 25 about 15% of the mass so that the syrup is widely distributed over the surfaces of the sugar crystals and substantially all of the syrup is brought into close and intimate contact with the sugar crystals, and then 30 evaporating water from the mass.

3. A method for crystallizing sugar from 35 solutions, comprising admixing sugar crystals with massecuite to form a mass having a relatively large quantity of sugar crystals comprising about 85% of the mass and a relatively small quantity of syrup comprising about 15% of the mass so that the syrup is widely distributed over the surfaces of the sugar crystals and substantially all of the 40 syrup is brought into close and intimate contact with the sugar crystals, and then cooling the mass and evaporating water therefrom.

4. A method for crystallizing sugar from 45 solutions, comprising admixing sugar crystals with massecuite to form a mass having a relatively large quantity of sugar crystals comprising about 85% of the mass and a relatively small quantity of syrup comprising about 15% of the mass so that the syrup is 50 widely distributed over the surfaces of the sugar crystals and substantially all of the syrup is brought into close and intimate contact with the sugar crystals, and then cooling the mass and then separating the remaining 55 adhering syrup from the sugar crystals by subjecting the mass to a particularly high centrifugal force.

5. A method for crystallizing sugar from 60 solutions, comprising admixing sugar crystals with massecuite to form a mass having a relatively large quantity of sugar crystals comprising about 85% of the mass and a relatively small quantity of syrup comprising about 15% of the mass so that the syrup is 65 widely distributed over the surfaces of the

sugar crystals and substantially all of the syrup is brought into close and intimate contact with the sugar crystals, then evaporating water from the mass and then separating the remaining adhering syrup from the sugar crystals by subjecting the mass to a particularly high centrifugal force. 70

6. A method for crystallizing sugar from 75 solutions, comprising admixing sugar crystals with massecuite to form a mass having a relatively large quantity of sugar crystals comprising about 85% of the mass and a relatively small quantity of syrup comprising about 15% of the mass so that the syrup is widely distributed over the surfaces of the 80 sugar crystals and substantially all of the syrup is brought into close and intimate contact with the sugar crystals, then cooling the mass and evaporating water therefrom and then separating the remaining adhering syrup from the sugar crystals by subjecting the mass to a particularly high centrifugal force. 85

7. A method for crystallizing sugar from 90 solutions, comprising admixing sugar crystals with massecuite to form a mass having a relatively large quantity of sugar crystals comprising at least 85% of the mass and a relatively small quantity of syrup, comprising 95 not more than 15% of the mass so that the syrup is widely distributed over the surfaces of the sugar crystals and substantially all of the syrup is brought into close and intimate contact with the sugar crystals, said syrup being in quantity sufficient to form a 100 film upon the crystals, cooling the mass, and then separating the adhering syrup from the sugar crystals by subjecting the mass to a particularly high centrifugal force. 105

8. A method for crystallizing sugar from 110 solutions, comprising admixing sugar crystals with massecuite to form a mass having a relatively large quantity of sugar crystals comprising at least 85% of the mass and a relatively small quantity of syrup, comprising 115 not more than 15% of the mass so that the syrup is widely distributed over the surfaces of the sugar crystals and substantially all of the syrup is brought into close and intimate contact with the sugar crystals, said syrup being in quantity sufficient to form a 120 film upon the crystals, and then cooling the mass. 115

9. A method for crystallizing sugar from 120 solutions, comprising admixing sugar crystals with massecuite to form a mass having a relatively large quantity of sugar crystals comprising at least 85% of the mass and a relatively small quantity of syrup, comprising 125 not more than 15% of the mass so that the syrup is widely distributed over the surfaces of the sugar crystals and substantially all of the syrup is brought into close and intimate contact with the sugar crystals, said syrup being in quantity sufficient to form a 130

film upon the crystals, and then evaporating water from the mass.

10. A method for crystallizing sugar from solutions, comprising admixing sugar crystals with massecuite to form a mass having a relatively large quantity of sugar crystals comprising at least 85% of the mass and a relatively small quantity of syrup, comprising not more than 15% of the mass so that 10 the syrup is widely distributed over the surfaces of the sugar crystals and substantially all of the syrup is brought into close and intimate contact with the sugar crystals, said syrup being in quantity sufficient to form a 15 film upon the crystals, then removing water from the mass, and then separating the remaining adhering syrup from the sugar crystals by subjecting the mass to a particularly high centrifugal force.

20 In testimony whereof I affix signature.
